UNITED STATES PATENT OFFICE

2,630,121

RECORD SHEET HOLDER

Frederick A. Niemann, Chicago, and Raymond J. Koch, Winnetka, Ill., assignors to Felt & Tarrant Manufacturing Company, Chicago, Ill., a corporation of Illinois

Application December 23, 1949, Serial No. 134,666

2 Claims. (Cl. 129—1)

1

This invention relates in general to record sheet holders, and more particularly to improvements in the backing support and the sheet clamping means thereof which facilitate their use with record sheets of different lengths.

Similar devices for facilitating the distribution of accounts are described and illustrated in United States Letters Patent No. 2,033,147, issued March 10, 1936, and No. 2,397,685, issued April 2, 1946, which maintain a plurality of record strips in desired parallel and overlapping relationship, with only a certain vertical column or columns of numerical data on each side of each strip exposed, to enable lateral addition or extension of the corresponding items in the various columns, with the assistance of a line guide or T-square. These prior devices include sheet clamping means, comprising a backing plate having upstanding pegs for receiving the sheets or record strips and a holding member cooperating with the pegs to retain the record sheets thereon, together with a board or backing support having a pair of pins adjacent its upper edge for receiving and positioning the sheet clamping means thereon and providing a lateral edge for guiding the T-square. However, the pins for receiving and positioning the sheet clamping means of such prior devices have been disposed only adjacent the upper edge of the backing support or board, so that the shorter the length of different record strips with which the devices are used, the more of the work of lateral extension must be done near the top of the board. Since this upper portion of the board necessarily is that part spaced farthest from the hand and eyes of the operator or person performing the cross-addition, work thereon is considerably harder and more tiring on the operator than that performed at the central and lower portions of the board.

A principal object of the instant invention, therefore, is to enable the performance of most of the cross-addition or lateral extension of items at the central and lower portions of the board or backing support of such a device for the distribution of accounts, regardless of the length of the record strips being used, in order to make such work easier on the operator and render its performance faster and more efficient. This is accomplished by providing novel pins, for receiving and properly positioning the record strip holding or sheet clamping means, that are removably positionable at selectively different points on the board or backing support spaced downwardly different distances from the

2

upper edge thereof to enable mounting of any of a plurality of different lengths of record strips on the board with their lower ends adjacent the lower edge of the board.

5 Another object is to enable ready reversal of the record sheets and their holding or clamping means on the backing support or board in any selected position of the receiving pins. In the prior devices previously referred to, such reversal was permitted because the sheet clamping means was mountable only on the upper edge of the board so that the holding member cooperating with the pegs on the backing plate could freely overhang the upper edge of the board when in reversed position thereon. The removable pins of the present invention are so constructed that they cooperate with the backing strip of the sheet clamping means to retain the latter in reversed position on the board, even when the pins are not disposed in their uppermost position directly adjacent the upper edge of the board, and despite the backing strip being required in its other positions on the board to assume an angular or other than horizontal position, when reversed, because of the sheet-receiving pegs and holding member thereon.

A further object of this invention is to facilitate selective positioning of the removable pins on the board or backing support by providing pin-receiving bushings in suitable locations on the board which are flush with the upper surface thereof, so as not to interfere with the record sheets and line guide when not in use, and which are provided with means cooperating with the upper portion of a pin to prevent rotation thereof relative to a separable lower portion of the pin to enable an operator to separate or attach the two portions of the pin with one hand.

Numerous other objects and advantages of the 40 invention will be apparent as it is better understood from the following description, which, when taken in connection with the accompanying drawings, discloses a preferred embodiment thereof.

45 In the drawings:

Figure 1 is a plan view, with parts broken away, of a record sheet holder embodying the features of the instant invention and showing a plurality of record sheets or strips held in parallel and overlapping relationship;

Fig. 2 is a side elevational view, as seen from the left end of Fig. 1;

Fig. 3 is a detail elevational view, as seen from the bottom of the device of Fig. 1;

50 Fig. 4 is an enlarged vertical section, taken

substantially on the line 4—4 of Fig. 1, and showing the sheet clamping or holding means in obverse position at the upper edge of the backing support;

Fig. 5 is a view similar to Fig. 4, with the pin for holding the sheet clamping means in elevation, showing the sheet clamping means in reverse position at the upper edge of the backing support;

Fig. 6 is a view similar to Fig. 5 showing the removable pin for receiving the sheet clamping means disposed in a selected position other than that adjacent the upper edge of the backing support, with the sheet clamping means retained thereby in reverse position on the board;

Fig. 7 is a top plan view of the upper sleeve of one of the pins for positioning the record sheet clamping means on the backing support;

Fig. 8 is an elevational view of the upper sleeve of the pin shown in Fig. 7, with a portion thereof in vertical section; and

Fig. 9 is a top plan view of one of the bushings mounted in the backing support for receiving the pins for positioning the record sheet clamping means.

Referring more particularly to Fig. 1 of the drawings, reference numeral 11 indicates a backing support or board of any suitable construction which is generally similar to that illustrated in Patents No. 2,033,147 and No. 2,397,685, previously cited. Along its left-hand edge, this board 11 is provided with a metal channel member 12 secured along its inner side to the bottom surface of the board by suitable screws 13 (Fig. 3), and terminating at its outer side in an upstanding flange which cooperates with a suitable slot 14 in the head portion 15 of a line guide or T-square 16. The board 11 also is provided with a plurality of supporting means or feet 17 (Fig. 2) to maintain the backing support in proper position upon the work surface of a desk or table in spaced relationship thereto, for a purpose to be later more fully explained. The backing support 11 also may be provided with a pair of elongated, folding leg members 18 adjacent its upper edge similar to those illustrated in U. S. Letters Patent Nos. 2,127,980 or 2,127,981, both issued August 23, 1938. The construction of these leg members 18 is such, as explained in these patents, that they may readily be disposed either in a folded position in substantially parallel relationship to the backing support, wherein the feet 17 will prevent contact thereof with the desk or other supporting surface, or in the extended position of Fig. 2 wherein they are perpendicular to the backing support and function to maintain the latter in an angular position on the supporting work surface or desk.

As a novel feature of the instant backing support or board 11, a plurality of bushings 19 are mounted therein adjacent each lateral edge (Fig. 1) which are arranged in transversely aligned pairs spaced from each other longitudinally of the board, with the upper such pair disposed adjacent the upper edge of the board. As best seen in Figs. 6 and 9, each of these bushings 19 is mounted in a suitable aperture 21 in the backing support 11, which is countersunk at its upper end to receive the flared upper end 22 of the bushing, these parts being so dimensioned that the upper end surface of the bushing is flush with the top surface of the board 11. This flared upper end 22 of each bushing is provided with a pair of diametrically opposed re-

cesses 23, for a purpose to be later described, which may be milled, in the manner illustrated in broken lines in Fig. 6, or otherwise suitably formed therein. After being mounted in an aperture 21, a suitable washer 24 is placed on the lower end of each of these bushings 19, and such lower end portion is spun, upset, or otherwise spread outwardly to its position of Fig. 6 to firmly engage the washer 24 and retain the bushing in assembled position in the manner of a rivet. To facilitate such displacement, this lower end portion of the bushing 19 is reduced in thickness, and this reduced portion terminates at its upper end to define an annular shoulder 25 which will be disposed substantially in the plane of the lower surface of the backing support 11 when the bushing is so mounted in an aperture 21 therein.

The instant record sheet holder also comprises a record sheet clamping or holding means indicated generally by reference numeral 26, generally similar to that illustrated in the two first cited prior patents and designated in No. 2,033,147 by reference numeral 11 and in No. 2,397,685 by reference numeral 12. This clamping means 26 comprises a backing plate 27 having a plurality of sheet-receiving pegs 28 (Figs. 1 and 4 to 6) upstanding therefrom and arranged in transverse alignment at regularly spaced intervals. These pegs 28 are adapted to receive a multiplicity of record sheets or strips 29 and maintain the same in desired parallel and overlapping relationship, the record sheets being provided with suitable apertures adjacent their upper ends to facilitate impaling the same on the pegs. As will be appreciated by those skilled in the art, each of these record sheets 29 may be provided with a plurality of vertical columns in which numerical data are entered, and the overlapping assembly of the strips will result in only a certain one or more of such columns of each strip being exposed to facilitate lateral addition or extension of the corresponding items in the various columns of the several strips. The record sheet holding means 26 also includes a channel-shaped holding member 30 which may be pressed down over the pegs 28 to frictionally engage the latter to retain the several record sheets 29 in proper position thereon. The backing plate 27 of the record sheet clamping means 26 is provided adjacent each end with a notch 32 in its lower or forward edge. The inner portion of each of these notches 32 is substantially circular and is countersunk from both sides of the backing plate (Fig. 5), while the outer portion thereof flares outwardly, being wider at its outer end and narrower at its inner end than the diameter of such circular inner portion. The edges of this outer portion of the notch or keyhole-shaped slot 32 are bevelled from both sides of the backing plate (Fig. 5) at the same angle as the associated countersinking of the circular inner portion thereof. The specific reason for such beveling of these notches will become more clearly apparent hereinafter.

Means are provided for receiving the record sheet clamping device 26 and maintaining the same in any selected one of a plurality of positions on the backing support or board 11, as determined by the arrangement of the bushings 19 therein, which comprises a pair of pins, indicated generally by reference numeral 33, removably mountable in desired ones of the bushings 19. As best seen in Fig. 4, each of these pins

comprises an upper portion made up of a sleeve 34 (Figs. 7 and 8) and a rod-like body portion 35 mounted therein, and a lower portion in the form of a sleeve 36. Intermediate its ends, the rod-like body portion 35 is provided with an enlarged flange 37 bevelled at the same angle as the key-hole slots 32, and the upper end of the bore of the upper sleeve 34 is slightly countersunk at this same angle (Figs. 7 and 8) to receive the lower end of this bevelled flange 37. The lower end of the rod-like body portion 35 has a washer 38 (Fig. 4) mounted thereon and retained in any suitable manner, as by means of a pin and slot connection 39, and a coil spring 41 is mounted thereon between this washer 38 and the lower end of the sleeve 34. This spring 41 thus resiliently maintains the lower end of the flange 37 seated in the upper countersunk end of the bore of the sleeve, while permitting, but resisting, upward movement of the rod 35 relative to the sleeve 34. The rod 35 terminates in an upper end 42 of somewhat greater diameter than the main body portion thereof, the diameter and length of this end portion 42 bearing a specific relationship to the dimensions of the record sheet clamping means 26, and particularly the keyhole notches 32 in the backing plate 27, in a manner to be later explained in detail.

As best seen in Fig. 8, the upper end of the upper sleeve 34 terminates in a flange or head portion shaped to conform to the countersunk or flared upper ends 22 of the bushings 19, including diametrically opposed and downwardly and outwardly extending lugs 43 adapted to be seated in, and engaged by, the recesses 23 of the bushings. The main body portion of this sleeve 34 has an outer diameter slightly less than that of the bore of the bushings 19, and is threaded on its outer surface at 44 at its lower end. The bore of the lower sleeve 36 is complementally threaded or tapped at its upper end to receive this lower threaded end 44 of the upper sleeve 34 (Fig. 4), and the outer surface of this lower sleeve preferably is knurled, as indicated at 45 in Fig. 5, to facilitate engagement and disengagement of the two sleeves comprising the pin 33. Such engagement or assembly and disengagement or detachment of the upper and lower portions of each pin 33 requires an operator to use only one hand, the interengagement of the lugs 43 in the recesses 23 preventing rotation of the upper portion of the pin when the latter is dropped into or disposed within one of the bushings 19. Since the shoulder 25 of each bushing 19 is disposed a predetermined distance below the upper end thereof, mounting of a pin 33 in any one of the bushings 19, as shown in Fig. 4, will result in the flange 37 and upper end 42 thereof being disposed in predetermined relationship relative to the upper surface of the 50 backing support or board 11.

Use is made of the above described record sheet holder in the following manner. The several record sheets 29, containing the items which it is desired to extend or cross add, first are mounted in proper overlapping relationship on a backing strip 27 by means of the apertures in the upper ends of the strips being impaled upon the pins 28 to expose those columns of the strips containing the items to be added, and the clamping or holding member 31 being pressed over the pegs 28. The backing support or board 11 is then placed on the work surface or desk, either with the foldable legs 18 extended in their position of Fig. 2 or retracted parallel with the board, as

best suits the convenience of the operator. It will be understood that when the legs 18 are in folded position, the feet 17 at the upper edge of the board will support the latter on the work surface, the legs 18 folding above the plane through the lower surface of such supporting feet. Depending upon the length of the particular record sheets 29 from which the data is to be taken, the operator will position the pins 33 in the proper bushings 19. As previously noted, several pairs of horizontally aligned bushings 19 are provided which are disposed in spaced relationship from the upper edge of the board 11 corresponding to the different standard lengths of record sheets 29 customarily employed. It will be understood also that the vertical length of the backing support 11 is determined by the maximum length of strip 29 used, and the pair of bushings 19 spaced farthest from the upper edge of the board are arranged in accordance with the length of the shortest record strips 29 to be employed. In the assembly illustrated in Fig. 1, since the record sheets 29 approach the maximum length for which the backing support 11 is designed to be used, the pins 33 have been mounted in the uppermost pair of bushings 19 adjacent the upper edge of the backing support.

It being assumed that the operator desires to distribute items on the obverse surfaces of these record strips 29, the sheet clamping means 26 in which the strips are held is engaged with the pins 33 in the manner best illustrated in Fig. 4. Such engagement is accomplished merely by sliding the clamping means 26 forwardly or downwardly to engage the pins 33 in the notches 32. Since the rearmost or narrowest end of the outer, flared portion of each of these notches 32 is narrower than the diameter of the inner, circular portion of these notches, such engagement of the clamping means 26 with the pins 33 will result in lifting of the rod-like body portion 35 of each pin against the action of its spring 41, as such narrowest portion of the associated slot 32 engages the lower bevelled surface of the pin flange 37. Continued forward or downward movement of the sheet clamping means 26 will result in the rods 35 of the pins 33 being seated by their springs 41 in the innermost, circular portions of the slots 32, as illustrated in Fig. 4. In such position, the pins 33 function to maintain the clamping means 26 and the record sheets 29 engaged thereby in proper alignment on the backing support 11, so that the corresponding items in the various columns of the record strips will be aligned with each other laterally of the backing support. The line guide or T-square 16 is then placed in operative position, as illustrated in Fig. 1, with the laterally extending straight-edge portion thereof disposed above the several record sheets 29. In this connection, it should be noted that the head 15 of the T-square 16 is provided with a cutout portion 46 along the upper surface of its inner edge to insure clearance between this part of the T-square and the lefthand end portion of the sheet clamping means 26 when the T-square is moved upwardly from its position of Fig. 1 for use in lateral extension of the items appearing on the strips 29 adjacent the upper ends thereof. Since the bushings 19 are mounted in the manner previously described with their upper ends flush with the top surface of the backing support 11, they will not interfere with vertical movements of the T-square during the process of cross-addition of the various items appearing upon the record strips.

Such arrangement of the record strips on the clamping means 26 not only exposes the desired columns on the upper surfaces thereof, but likewise exposes corresponding columns on the reverse sides of the strips. Consequently, the operator may distribute such items merely by reversing the position of the record strips and the clamping means 26 to expose such reverse sides. When the retaining pins 33 are disposed in the uppermost pair of bushings 19 as illustrated in Figs. 1 and 4, this reversal may be accomplished merely by sliding the clamping means 26 upwardly to disengage the same from the pins, turning the clamping means over end-for-end, and re-engaging the notches 32 with the pins 33 in the manner illustrated in Fig. 5. Such engagement of the record strip clamping means 26 with the pins 33 is enabled by virtue of the uppermost pair of bushings 19 being disposed adjacent the upper edge of the backing support 11, so as to provide clearance for the pegs 28 and holding member 31 beyond the upper end of the backing support. It should be noted also that the feet 17 are sufficiently long not only to prevent contact of the holding member 31 with the work surface, when the clamping means 26 is disposed in this reversed position at the upper edge of the backing support as illustrated in Fig. 5, but also prevent contact of the lower ends of the pins 33 with the work surface.

Whenever it is desired to use the instant record sheet holder with strips 29 of shorter length, it is necessary only for the operator to unscrew the lower sleeve 36 of each pin 33 from its upper sleeve 34, lift the upper portion of the pin out of the bushing 19 in which it was mounted, drop the same into one of the pairs of bushings 19 selected according to the particular length of the record sheets 29 next to be used, and re-engage the lower sleeve 36 with the upper portion of the pin. Such separation and reassembly of the two portions of a pin 33 may be accomplished by the operator with the use of only one hand because engagement of the lugs 43 on the upper sleeve 34 with the recesses 23 in the bushings 19 prevents rotation of the upper sleeve. It also should be noted that the upper sleeve 34, rod 35 and spring 41 of each pin 33 always are retained in assembled relationship, so that this upper portion of the pin may readily be lifted from, or inserted 45 into, any of the bushings 19. When in mounted position, as shown in Fig. 4, the lower sleeve 36 also functions to protect the spring 41 and the lower end of the upper portion of the pin against any possible physical damage.

When mounted in any pair of bushings 19 other than the uppermost ones, the pins 33 will engage the slots 32 of the record sheet holding means 26 in the manner illustrated in Figs. 1 and 4 when the clamping means and the strips retained thereby are in their obverse position on the board. However, it is not possible for the record clamping means 26 to assume its reversed position of Fig. 5, with the backing plate 27 parallel to the board 11, if it is desired to reverse the record sheets 29 on the backing support when the pins 33 are in any such position other than in engagement with the uppermost pair of bushings 19. Such reversal may be accomplished, nevertheless, and the record sheet clamping means 26 securely retained in reversed position by virtue of the upper end portions 42 provided on each of the pins 33. The record strip clamping means 26 is shown in Fig. 6 in such reversed position in engagement with a pin 33, when the

sheet clamping member and a backing support therefor having an aperture therethrough; a retaining device mountable in said aperture in the backing support to maintain the record sheet clamping member in proper position thereon, comprising a main body member having means formed integrally with the upper end thereof for engaging the clamping member, an upper sleeve positionable in the aperture in the backing support and slidably engaging the central portion of said body member, means on said upper sleeve to prevent passage thereof through said aperture, spring means mounted on the lower end of said main body member for resiliently interconnecting the same and said upper sleeve, and a lower sleeve screw-threadedly engaging said upper sleeve for cooperation with the backing support to secure the upper sleeve in the aperture therein and covering said spring means to prevent injury thereto.

2. In a record sheet holder including a record sheet clamping member and a backing support therefor having an aperture therethrough; a retaining device mountable in said aperture in the backing support to maintain the record sheet clamping member in proper position thereon, comprising a main body member having means formed integrally with the upper end thereof for engaging the clamping member, an upper sleeve positionable in the aperture in the backing support and slidably engaging the central

portion of said body member, spring means mounted on the lower end of said body member for resiliently connecting the same and said upper sleeve, a lower sleeve screw-threadedly engageable with said upper sleeve for cooperation with the backing support to secure the upper sleeve in the aperture therein, and interengageable lugs and recesses on said upper sleeve and the backing support to prevent passage of said upper sleeve through said aperture and to facilitate attachment and detachment of said lower sleeve by preventing rotation of said upper sleeve when the same is positioned in the aperture in the backing support.
